BOOK HOLDER

Henry C. Stoll, New York, N. Y.

Application January 12, 1939, Serial No. 250,457

1 Claims. (Cl. 211—43)

The invention herein disclosed relates to book holders.

Special objects of the invention are to provide a device for holding one or a number of books in proper order, which will be particularly neat, attractive and ornamental in character.

The foregoing and other desirable objects are attained in the present invention by novel features of construction, combinations and relations 10 of parts all as hereafter described, illustrated in the accompanying drawing and broadly covered in the claim.

The drawing illustrates a preferred embodiment of the invention, the actual structure being 15 capable of change and modification in various ways all within the true intent and broad scope of the invention.

Fig. 1 is a broken part sectional elevation of one form of the holder.

Fig. 2 is a partly broken end elevation of the same.

In the embodiment illustrated, the base 15, is in the form of a board or elongated panel of wood or other suitable material, which can be placed 20 on a desk, table or any other suitable support. A special feature of this base is that it has an undercut groove extending the length of the same and shown particularly in Fig. 2, as consisting of a surface slot 16, a widened trackway 25 17, below that and a narrower bottom groove 30 18, below such trackway.

The bookends consist in this embodiment of the relatively thin sheet metal uprights 19, punched or otherwise shaped to form various animal or other ornamental designs and having dependent lugs 20, 21, extended down through and upset or riveted in the flat base plates 22, designed to slide in trackway 17.

The outer lugs 20, are shown as extended somewhat to provide hooks or abutments 23, over

which are looped the ends of a coiled expansion spring 24.

The upstanding portions of the bookends are shown as having upper and lower book engaging portions 25, 26, separated by an intervening finger receiving space 27, assuring firm holding of the books and providing a ready finger grip by which the ends may be readily separated, against the holding force of the spring connecting the ends.

The two opposed spring connected bookends can be handled as a unit in sliding them into or removing them from the undercut groove in the supporting base. An intermediate stop 36 may be interposed in the undercut groove or trackway 15 17 between the sliding book-end bases 22.

The structure while relatively simple and inexpensive is entirely practical and desirable and can be made up in many ornamental and attractive forms, to suit or to be actually physically 20 combined with special furniture, such as end tables, desks, cabinets and the like.

What is claimed is:

A book holder, comprising a supporting base having a narrow surface slot in the face of the 25 same, a wider laterally extended trackway beneath said slot and a narrow bottom groove below said trackway, book ends having narrow thin flat bases slidably supported on and confined in said trackway below the surface of said 30 supporting base and upstanding portions projecting from said bases up through said narrow surface slot into opposing book holding relation and a coiled spring housed within said bottom groove below said book end bases and connected 35 at opposite ends with said sliding bases to thereby yieldingly draw said book ends together, thus slidably supported wholly beneath the surface of said supporting base.

HENRY C. STOLL.
